(57) **CLAIM**

The ornamental design for a flashlight, as shown and described.

DESCRIPTION

FIG. 1 is a perspective view of a flashlight showing my new design;
FIG. 2 is a top view thereof;
FIG. 3 is a first side view thereof;
FIG. 4 is a second side view thereof;
FIG. 5 is a bottom view thereof;
FIG. 6 is a back view thereof; and
FIG. 7 is a front view thereof.

The broken lines immediately adjacent to the shaded areas depict the bounds of the claimed design, while all other broken lines are directed to the environment. The broken lines form no part of the claimed design.

1 Claim, 2 Drawing Sheets
